UNITED STATES PATENT OFFICE.

EUGENE A. RIOTTE, OF BRONXVILLE, NEW YORK, ASSIGNOR TO STANDARD MOTOR CONSTRUCTION COMPANY, OF JERSEY CITY, NEW JERSEY, A CORPORATION OF NEW JERSEY.

CARBURETER.

1,074,575.

Specification of Letters Patent. Patented Sept. 30, 1913.

Application filed January 16, 1912. Serial No. 671,466.

To all whom it may concern:

Be it known that I, EUGENE A. RIOTTE, a citizen of the United States, residing at Bronxville, Westchester county, State of New York, have invented certain new and useful Improvements in Carbureters, of which the following is a full, clear, and exact description.

My invention relates to improvements in vaporizers for internal combustion engines and consists in an improved embodiment of that type of vaporizer set forth and claimed in United States Letters Patent numbered 1,006,130, dated October 17th, 1911.

15 The main object of the present invention is to simplify and render more compact said construction and better adapt the same to use on relatively small engines of the internal combustion variety.

20 In the drawings, Figure 1 is a vertical sectional view illustrating the several parts in operative position. Fig. 2 is a horizontal sectional view on the plane of the line $\alpha-\alpha$, Fig. 1. Fig. 3 is a development view of the sleeve with the sprayer tips shown in dotted lines.

1 represents the casing of a reservoir arranged to hold liquid fuel which is admitted through a pipe 2.

30 3 is a valve ordinarily controlled by a float 4 which valve controls the fuel admission duct to maintain said fuel at a proper level within the casing 1.

35 5—5 represent a plurality of open ended sprayer tips at the upper ends of pipes which lead down into the fuel casing 1 so that their lower ends will be immersed in the liquid fuel therein.

40 6 represents a mixing tube connected to the upper part of the casing 1, preferably in the manner hereinafter described, which tube 6 also constitutes the feed pipe leading to the motor. 7 represents a manually controllable throttle or damper therein. The

45 pipe 6 at its lower end is preferably provided with a foot or flanged portion 8 which overstands the reservoir 1, said reservoir, of course, being closed at the top against the escape of fuel. This flange 8 is spaced

50 apart from the top of the reservoir somewhat so as to provide an annular air admission passage leading into the mixing chamber. The foot 8 is connected to the reservoir casing by legs 9—9 provided in any suitable number. As shown, the open ended

tips or fuel supply nozzles 5—5 project into said passage so that as the draft of air rushes through the admission passage and over the aforesaid tips, fuel will be drawn up to mix with the entering air to form the mixture in the carbureting chamber.

10 is a tubular sleeve by which the area of the inlet passage may be manually regulated. This regulating sleeve may be mounted in the foot piece of the pipe 6 and may be adjustable up and down by any suitable means; for example, the tubular portion of said foot piece may have an oblique slot 11 cut therein. 12 is a screw which passes through said slot and screws into the sleeve 10. By loosening the screw, it may be used as a handle to partially turn the sleeve 11 so that, as the sleeve is turned, the screw will move up or down the inclined slot 11, and will thereby raise or lower the regulating sleeve to vary the area of the inlet passage to the desired extent, thereby making it easy to adjust the vaporizer to different motors. When the desired adjustment of the regulating sleeve 10 has been effected, the screw 12 may be tightened up to hold it fixedly in said regulated position.

The means for automatically controlling the volume of mixture, and for preserving the proper proportion of fuel relatively to air, comprises an automatically operable sleeve 14 which slides up and down in a guide tube at the center of the reservoir 1. This sleeve 14 is closed at its lower end by a partition 15 so that it may act as a piston. 90 The lower end of the tube in which the sleeve 14 moves is also closed as at 16 excepting for a small external duct or bleed passage 17 to form a dash pot. The bleed passage 17 vents the dash pot and permits 95 said piston-like sleeve 14 to ascend and descend with not undue speed. If desired a controlling valve 18 may be employed to control the size of the bleed passage 17. The sleeve 14 extends above the air admission passage at the foot of tube 6 so that, were it not for openings in the sides of the sleeve, said passage would be closed. I provide, however, suitable openings in the side walls of said sleeve, so designed that, when 100 the sleeve is fully down or in its lowermost position, it nearly cuts off said passage. As soon as a vacuum in the carbureting chamber is created, this vacuum lifts the piston sleeve 14, at which time the admission pas- 110

sage adjacent the fuel device is correspondingly opened to admit more air. The preferred form of openings in the piston sleeve 14 are best seen in the development view, Fig. 4, in which A—B—C represent said openings, all of which are narrowest at the top and widen toward the bottom, one edge of each opening being preferably substantially vertical, the other edge being inclined. 10 The sprayer tips 5—5 are so arranged around the air admission passage that as the piston sleeve 14 ascends, the said tips will be progressively uncovered to the current or draft of inrushing air. In the particular 15 form shown, there are nine tips provided and the relative position of said tips is indicated conventionally in the development view, Fig. 4. In the form shown in that view, one of the openings A has a slight upward extension A' which, even though the piston sleeve 14 stands in its lowermost position, will afford a slight opening at least for the admission of air adjacent to one of the tips 5 whereby, the moment the engine is 20 started and the vacuum created, a mixture of air and gas will be provided.

19 is a weight which may be detachably secured to the piston sleeve 14, which weight may be varied to adjust the piston for 30 proper action with different engines.

Obviously, when the carbureter is designed for any particular engine, the piston sleeve 14 may be made of the proper weight at the outset, but inasmuch as said carbureters may be applied to different engines, it is desirable to provide means for easily 35 modifying the weight of said piston.

From the foregoing it will be seen that it is the force of gravity that is relied upon 40 to move the piston sleeve 14 downwardly, the upward movement thereof being secured by a partial vacuum in the carbureting tube or chamber.

To guard against admission of dust or 45 dirt, a screen 20 may be provided around the legs 9—9. While the construction of the vaporizer itself is such that the admission of dust will not impair its action, it is exceedingly undesirable to permit dust or 50 dirt to enter the engine cylinders or pass the valves thereof.

It will be observed that in operation the 55 automatic throttle is in effect in free suspension, it being upheld by the tension of air in the carbureting chamber which remains substantially constant. Of course, as a greater volume of mixture is demanded and the throttle is opened to provide such increased volume, there will be a momentary 60 tendency to increase the tension or vacuum which will lift the automatic throttle at a higher level, but inasmuch as the raising of the throttle admits an increased volume of air, the said increased volume will be found 65 to be in such proportion as to supply a suffi-

cient quantity of air to the carbureting chamber to preserve the initial air tension or vacuum, which, as above suggested, remains substantially constant irrespective of the volume of mixture being formed and transferred through the feed pipe. 70

Since the preferable construction contemplates the utilizing of the weight of the automatic throttle to counteract the lifting tendency of the vacuum, and since a weight 75 is a constant, it follows that there will be the greatest accuracy in the operation of the instrument.

While the piston or dash pot effect above referred to prevents abnormally quick movement of the throttle when the apparatus is subjected to quickly varying loads, it also is of decided advantage when the apparatus is used on automobiles traveling over rough roads where said apparatus will be subjected 85 to heavy vibration, for in such case, it will be found that such vibration will have no perceptible influence on the throttle by reason of the checking action of said piston or dash pot. One simple means for guiding the 90 automatic throttle sleeve may comprise a fixed guide-pin standing in a vertical slot 95 22 in said sleeve.

What I claim is:

1. In a carbureter, a carbureting chamber, 95 an air admission passage at the base of the same and extending around the same, means for manually varying the area of said passage, a plurality of open-ended fuel supply nozzles arranged around said carbureting chamber and adjacent to said air admission passage, an automatically controllable throttle comprising a piston sleeve, the walls of said sleeve having vertical openings therein which are narrow at the top and widen 100 downwardly, said sleeve overstanding said air admission passage, a piston at the lower end of said throttle, a dashpot at the lower end of said piston having a relatively small external vent to permit said portion to slowly 105 ascend and descend and to thereby permit said throttle to slowly ascend and descend to vary the effective size of the air entrance passage and to progressively expose said nozzles to the draft of air through said passage as said throttle ascends and to progressively cut out of the line of draft said fuel supply nozzles as said throttle descends. 110

2. In a carbureter, a tubular carbureting chamber having an annular air admission passage at its lower end, a plurality of open-ended fuel supply nozzles arranged around said opening and in front of the same, a sleeve-like throttle arranged to move up and down in said tubular carbureting chamber, and a tubular guide for said throttle below 120 said air admission passage, said tubular guide being closed excepting for a relatively small vent at its lower end, said sleeve being closed at its lower end, the sides of said 125 130

sleeve being slotted, said slots being narrow at the upper part and increasing in width downwardly whereby a vacuum in said mixing chamber will raise said sleeve and open 5 said air passage more and more as said sleeve ascends and simultaneously and progressively expose said nozzles progressively to the influence of the draft of entering air, said piston descending by gravity as said 10 vacuum decreases, correspondingly reducing the effective area of the air admission passage and correspondingly cut out of the line of draft progressively the said fuel supply nozzles.

15 3. In a carbureter, an annular liquid fuel reservoir, a tubular carbureting chamber mounted concentrically thereabove and

spaced apart therefrom forming an air admission passage direct to the atmosphere on all sides, a concentric guide tube within the 20 reservoir, means for manually varying the area of said passage, a plurality of open ended supply nozzles arranged around said carbureting chamber and entering said air passage, an automatically controlled throttle comprising a piston sleeve sliding in said tube and guide, the walls of said sleeve having vertical openings therein which are narrower at one end and widened toward the other end.
